[57]

CLAIM

The ornamental design for a cutter bit, as shown and described.

DESCRIPTION

FIG. 1 is a side elevational view of the cutting bit showing my new design, the rear being a mirror image thereof;

FIG. 2 is a side elevational view taken from the right of FIG. 1; the side opposite being a mirror image thereof;

FIG. 3 is a bottom plan view thereof; and FIG. 4 is an enlarged perspective view thereof.
